UNITED STATES PATENT OFFICE.

WILLIAM T. SEE, OF MEADVILLE, PENNSYLVANIA.

TRAIN-ORDER-DELIVERING DEVICE.

1,026,467.

Specification of Letters Patent. Patented May 14, 1912.

Application filed August 26, 1911. Serial No. 646,175.

To all whom it may concern:

Be it known that I, WILLIAM T. SEE, a citizen of the United States, residing at Meadville, in the county of Crawford and 5 State of Pennsylvania, have invented new and useful Improvements in Train-Order-Delivering Devices, of which the following is a specification.

This invention relates to devices for delivering train orders or messages to engineers or conductors of moving trains, the object of the invention being to provide a device of this character which will possess such improvements over my Patent #972,654, of 10 October 11, 1910, as will permit of the device being manufactured at less expense and which will include novel retaining means for the message.

Another object of the invention is to provide a message holder which will include a collecting and grasping member and a handle member, the former being removably mounted on the latter so that it may be collected when grasped by the hand of the 25 receiver.

In the drawing, forming a portion of this specification and in which like numerals of reference indicate similar parts in the several views: Figure 1 is a perspective view 30 of the message holder. Fig. 2 is a longitudinal section through a portion of the same.

My improved train order delivering device or message holder comprises a collecting and grasping member 1 which is preferably constructed of wire bent in ring form and covered if desired by a suitable padding 2. The terminal 3 of the ring forming wire is offset, at 4, and secured 35 by solder or otherwise suitably fastened to the terminal 5 of the wire. The said terminal 3 extends outwardly from the terminal 5, as shown at 6, to form an intervening substantially V-space 7 between the portions 5 and 6 for the reception of the message. The portion 6 has its end 8 extended 40 in the direction of the ring and it is looped therearound, at 9. The portion 6 is yieldable so that the message may be securely 45 confined between the portions 5 and 6 and held in the space 7 against accidental displacement.

The handle 10 of the device is provided 50 at its outer end with a socket 11 in which the intertwined terminals 12 of the arms 13 are engaged and securely confined therein.

The arms 13 extend in opposite directions from each other and collectively they form a fork of substantially semispherical configuration. The outer ends of the arms 13 are provided with substantially U-sockets 14 which are designed to receive the opposite sides of the ring member 1, as shown clearly in Fig. 1 of the drawing. The arms 13 are movable relatively and are yieldable or 60 somewhat elastic so that normally they will yieldingly engage against the ring 1 to hold the same securely in receiving position. With a view of preventing partial rotation of the ring member in the supporting arms 65 13, I provide the handle with a retainer 15 having a forked outer portion 16 whose arms are adapted to straddle the inner portion of the ring 1, as shown.

The device as described is extremely simple, it may be manufactured at a relatively low cost and used in a convenient manner for delivering train orders or messages, obviating the necessity of stopping the train to receive such orders. In operation, the 70 handle portion of the device is held in the hand of the one delivering the message so that the ring portion is positioned for convenient reach of the engineer who may collect the device by grasping the ring portion 75 so as to remove the same, with the message from the handle.

The device as constructed herein may be manufactured at a relatively low cost and in use the device will be found most desirable in that the liability of injury to the ones holding and receiving the device will be entirely obviated, incident to the fact that the handle portion 10 of the device is not removed from the hands of the one holding 90 the message. It will of course be understood that in operation when pull is exerted on the ring 1 by the receiver of the message it may be readily removed from the supporting arms 13 and without liability of the message 95 becoming lost or destroyed.

I claim:

1. A message holder comprising a supporting member having yieldable arms thereon, the said arms having sockets therein, a message retaining device having portions fitting in the sockets of said yieldable arms, and means on the supporting member for holding the message retaining device operatively associated with said yieldable 105 arms.

2. A message holder comprising a sup-

porting member, a message retaining device, means on the supporting member for engaging the supporting device to hold the same in hand-receiving position, and second means on the supporting member for engaging the message retaining device to hold the same operatively associated with the first means.

3. A message holder comprising a handle member, yieldable arms thereon, the said arms having socket portions thereon, a ring removably fitted in the socket portions, a

forked member carried by the handle member and having spaced arm portions extending against the sides of the ring to hold the ring against rotation in the arms, and a message retaining device carried by the ring.

In testimony whereof I affix my signature in presence of two witnesses.

WILLIAM T. SEE.
